186,280

HANDLE FOR COFFEE MAKER OR SIMILAR ARTICLE

George S. Tarbox, Yonkers, N.Y.

Application January 7, 1958, Serial No. 49,162

Term of patent 14 years

(Cl. D44—29)

Fig. 1 is a view in perspective of a handle for coffee maker or similar article showing my new design.

Fig. 2 is a top plan view of the handle.

Fig. 3 is an elevational end view of the handle.

Fig. 4 is a view in side elevation of the handle.

I claim:

The ornamental design for a handle for coffee maker or similar article, as shown.
